Inventor:

Jacob Heed

United States Patent Office.

JACOB HEED, OF TEMPERANCEVILLE, OHIO.

Letters Patent No. 66,339, dated July 2, 1867.

CHIMNEY.

The Schedule referred to in these Letters Patent and making part of the same.

TO ALL WHOM IT MAY CONCERN:

Be it known that I, JACOB HEED, of Temperanceville, Belmont county, and State of Ohio, have invented a new improvement on Chimneys; and I do hereby declare that the following is a full and exact description thereof, reference being had to the accompanying drawing, and to the letters of reference marked thereon.

The nature of my invention consists in the following alterations in the original mode of building chimneys, by which a much greater heat is obtained from the same amount of fuel, and much better draught produced, and great saving of material in building the same, and all built of brick or stone.

In order to enable others skilled in the art to make and use my invention, I will proceed to describe its construction and operation. In the drawing—

Figure 1 is a perspective view of my chimney. The diaphragms or partitions are indicated by dotted lines.

Figure 2 is a perspective view of the lower diaphragm, and

Figure 3 is a second diaphragm.

I construct my chimneys in the usual form externally. Near or at the throat of the fire-place the back wall is provided with two or more projections, similar to those marked A A in the accompanying drawing, varying of course in number and depth according to the size and depth of the fire-place, instead of all previous plans, by which means all the heat produced is equally distributed over the room instead of it all being thrown on the hearth, as is the case with those already patented. From the top of the fire-place my chimneys are built with a single wall where other chimneys are built solid, leaving a small flue, thereby saving much material in building, leaving the entire chimney above the fire-place hollow. From eight to eighteen inches above the fire-place, varying according to size of chimney, (the larger the higher,) I place a diaphragm, B, which is built from each wall inwards till it covers the entire space of the chimney, leaving a cylindrical aperture, E, containing more square inches than the throat of the chimney; and in houses of tall story I place another diaphragm D, very similar to diaphragm B, with a cylindrical aperture, H, larger than that of B, and in like manner making one diaphragm for each story, with an aperture of the same shape, and each aperture larger than the one next below, and also one in the top.

I claim as my improvement, and desire to secure by Letters Patent—

In a chimney, constructed as described, the projections A A and the diaphragms B D, one or more, each provided with an aperture, and arranged substantially as described and for the purposes specified.
